UNITED STATES PATENT OFFICE.

HARRY CLAY TAZEWELL, OF WILMINGTON, DELAWARE.

CAR-WHEEL.

SPECIFICATION forming part of Letters Patent No. 688,898, dated December 17, 1901.

Application filed March 23, 1901. Serial No. 52,578. (No model.)

To all whom it may concern:

Be it known that I, HARRY CLAY TAZEWELL, a citizen of the United States, residing at Wilmington, in the county of Newcastle 5 and State of Delaware, have made certain new and useful Improvements in Car-Wheels, of which the following is a specification.

My invention is an improvement in car-wheels, relating particularly to the construction of the wheel, whereby to provide means for lubricating the same, for securing it upon the axle, and for preventing the ingress of dust or the like between the wheel and the box; and the invention consists in certain novel 15 constructions and combinations of parts, as will be hereinafter described and claimed.

In the drawings, Figure 1 is a longitudinal section of a car-wheel in place on an axle, parts being broken away. Fig. 2 is an elevation of the outer end of a car-wheel in place on an axle, parts being broken away. Fig. 3 is a detail view illustrating the means for preventing the accidental overturning of the screws which coöperate with other features 25 in securing the wheel upon the axle. Fig. 4 is a detail view of one of the sections of the split collar, and Fig. 5 is a sectional view on about line 5 5 of Fig. 1.

The wheel A has its body portion B provided with an oil-chamber C, from which ports D lead to the bearing E of the wheel. It will be noticed that these ports are arranged between the outer and inner ends of the oil-chamber C. This is important, as it provides 35 portions between the said oil-ports D and the outer and the inner ends of the oil-chamber in which the oil can settle when the wheels are set on end, thus preventing the wasting of oil when the wheels are in such position. 40 In this connection it will be noticed that the chamber C is closed at its opposite ends, and a plug-filled opening F is provided, by which oil can be supplied as desired. In practice suitable wicks G are provided in the ports D, 45 leading from the oil-chamber C to the spindle-bearing and operate to feed the oil to such bearing, as desired. At its inner end the hub of the wheel is provided within its bore with a rabbet or groove H, which extends entirely 50 around it and registers with a groove or rabbet I in the box J, which box is also provided with an arm or portion K, which overlies the

inner end of the wheel-hub. The grooves H and J form a recess in which is fitted a packing L, usually of felt, and which when wet 55 with oil expands closely and snugly against the axle, thereby excluding all dust or foreign matter from the bearing of the wheel. By thus fitting the packing L in coinciding and communicating grooves the packing is caused 60 to lap the joints between the wheel and the box, and thus operates efficiently to prevent the entrance of dust or the like. The axle M has its spindle N provided near its outer end with an annular groove at O, in which 65 is fitted the two halves or sections P of a split collar, which sections are provided in their circumferential faces with grooves Q, in which project the inner ends of screws R, whose outer ends are provided with the angular heads S, by which they may be turned, and at the base thereof with outwardly-facing shoulders T. The outer end of the wheel-hub is formed with a cap which fits over the outer end of the spindle N, and such hub is 70 provided with suitable threaded openings for the bolts R and adjacent to such openings with the bosses U, which are provided with openings for the split key V, which when inserted, as shown in Figs. 1, 2, and 3, will over- 75 lie the shoulder T of the bolt and prevent said bolt from jolting out of place or being otherwise accidentally removed. As shown in Fig. 3, the space between the bosses U is curved inwardly at W for the passage of the shoulder T in inserting and removing the bolt when the key V is withdrawn. 80

By the described construction the wheel is so formed as to prevent the entrance of dust or the like at its outer end, is secured at such 90 end upon the spindle so it can be readily removed when desired, is free to turn upon the spindle, and the devices for holding the wheel on the spindle are so secured as to prevent them from being accidentally withdrawn. 95

Having thus fully described my invention, what I claim as new, and desire to secure by Letters Patent, is—

1. The improvement herein described, consisting of the axle having its spindle provided near its outer end with a circumferential groove, the split collar fitted in said groove, and having its sections provided in their circumferential faces with grooves for the fas- 100

tening-bolts, the box provided in its outer end with a circular groove or rabbet, the wheel having the inner end of its hub provided with a circular groove or rabbet registering with 5 that in the box and having its body portion provided with an oil-chamber closed at its outer and inner ends and provided between said ends with ports leading to the bearing whereby the wheel when set on end will be 10 provided with recesses or cavities for holding the oil, such wheel being provided at the outer end of its hub with openings in register with the grooves in the split-collar sections and at the outer ends of said openings with 15 bosses, the bolts fitting in said openings and projecting at their inner ends into the grooves in the split-collar sections and having shoulders at their outer ends, and the keys held to the bosses and overlying the said shoulders, 20 substantially as set forth.

2. The combination of the spindle provided near its outer end with a circumferential groove, the split collar having its sections fitted in the said groove and provided in their 25 circumferential faces with grooves, the wheel having its hub fitting over said spindle and

split sections and provided with openings registering at their inner ends with the grooves in the collar-sections, and provided at their outer ends with bosses having openings for 30 keys, the bolt fitting in the openings in the hub projecting at their inner ends into the grooves in the collar-sections and provided at their outer ends with outwardly-facing portions resting adjacent to the bosses of the 35 wheel-hub, and the keys held in said bosses and arranged to secure the bolts in the hub, substantially as set forth.

3. The combination of the spindle provided near its outer end with a circumferential 40 groove, the collar-sections fitted in said groove and provided in their circumferential faces with grooves, the wheel-hub fitted over said collar-sections and having openings for the securing-bolts and the bolts fitting in said 45 openings and projecting at their inner ends into the grooves in the collar-sections, substantially as set forth.
